UNITED STATES PATENT OFFICE.

IRVIN C. SMITH, OF LOS ANGELES, CALIFORNIA.

VALVE-GRINDER.

942,222.

Specification of Letters Patent.

Patented Dec. 7, 1909.

Application filed December 21, 1908. Serial No. 468,502.

To all whom it may concern:

Be it known that I, IRVIN C. SMITH, a citizen of the United States, residing at Los Angeles, in the county of Los Angeles and State of California, have invented new and useful Improvements in Valve-Grinders, of which the following is a specification.

In the operation of grinding valves, conical or other circular valves which may be rotated on their seats, it is desirable to not rotate the valve through a whole revolution on the seat as such an operation is not conducive to true grinding. The best motion which can be obtained is one of oscillation through a small angle, the valve being removed from the seat from time to time to allow a rearrangement of the grinding powder which is introduced between the valve and the seat. The motion given by the fingers grasping the valve stem and oscillating the stem is precisely the motion desired but the tediousness of the operation is infinite. Moreover the length of time necessary for the grinding of a valve by hand is quite extensive and the results are not so uniform as when performed by the aid of a machine.

The present invention relates to a valve grinder which is of simple construction and which duplicates the motion above described.

The main object of construction has been to make the machine as simple as possible so as to reduce the cost to a minimum and at the same time to make the machine efficient in its workings.

The invention consists broadly in a cam mechanism to oscillate a shaft to which the valve is connected by an appropriate means.

It is particularly in the arrangement and construction of the shaft and the cam that the invention lies and this will be more clearly understood from the following description and the accompanying drawings, in which.—

Figure 1 is a sectional side elevation showing the grinder in use. Fig. 2 is a front elevation of the grinder with a different style of connecting tool therein. Fig. 3 is a section taken on line 3—3 of Fig. 1.

Referring now more particularly to the drawings, 5 designates a frame which, in the present construction, is of a general U-shape as that shape most conveniently accommodates the mechanism of the grinder. The frame is provided with a handle 6 on

its upper part by means of which the whole machine may be supported and steadied when in use.

Mounted in the outer ends of the frame is a vertical shaft 7, being free to revolve but held against longitudinal movement by being set in a closed ended hole in the upper part of the frame and having a collar 8 secured on it above the lower part of the frame. The shaft projects below the frame and is provided with a sleeve 9 set thereon and projecting beyond its end for the reception of the connecting tool. A set screw 10 is provided for the securing of the connecting tool in the sleeve.

Mounted in the bearing 11 on the frame is a transverse shaft 12 having a crank handle 13 set on its end so that it may be rotated manually. Mounted on the shaft on the inside of the frame is a cam 14, the curve of the cam lying in a cylindrical surface whose axis is parallel to the shaft. The cam is provided with an uneven number, in this case three, of raised portions 15 and the same number of depressions 16 between the raised portions. Secured to vertical shaft 7 is a transverse arm 17 which carries on its ends rollers 18 engaging with the curved face, of cam 14. The configuration of the face, and the angle it makes to the shaft, are such that both rollers are continually in touch with the face, a smooth movement of the rollers and the arm being thereby effected. This condition will be most clearly seen by reference to Fig. 3 where the cam is shown in cross section. The angle of the cam face to the cam shaft varies as the face proceeds around the cam so that the rollers always follow flatly upon the face. This variation is shown most clearly in Fig. 1 where the high-portions are shown to have faces sloping in one direction and the low portions faces sloping in the opposite direction.

In the operation of this device a suitable connecting tool is set in the lower end of sleeve 9 with the aid of set screw 10. In the drawings a screw driver 20 with a long shank 21 is shown in Fig. 2. It will be understood, however, that the tool forms no part in the invention and that it may be changed as desired. The screw driver is placed in engagement with the valve, a spring 24 being placed under the valve to normally hold the valve off seat 25. A suitable grinding material having been placed

between the valve and the seat, the valve is forced down upon the seat with a proper pressure upon handle 6. After turning crank 13 for a short time the pressure is removed from the handle and the valve allowed to rise off the seat, spring 24 being of sufficient strength to raise the valve and the grinder. The operation is repeated as many times as desired for the thorough fitting of the valve and seat.

From the foregoing it will be seen that the invention consists broadly in the combination of an oscillating shaft with a manually operated cam for actuating the shaft. The minor points of construction may be varied to suit any class of work, the form shown being particularly adapted to the grinding of small valves such as are used in automobile engines and the like.

Having described my invention, what I claim is—

1. A valve grinder, comprising a frame having a handle thereon for manual oper-

ation, a vertical shaft journaled in the frame, a tool connected to the shaft for engagement with a valve, a transverse shaft journaled in the frame, a cam mounted on the transverse shaft, the cam having a face whose curves lie in a cylindrical surface around the shaft, and a cam follower mounted on the vertical shaft.

2. A valve grinder, comprising a frame, a longitudinal shaft journaled in the frame, means on the shaft for engagement with a valve, a transverse shaft journaled in the frame, a cam mounted on the transverse shaft, and a cam follower mounted on the longitudinal shaft.

In witness that I claim the foregoing I have hereunto subscribed my name this 14th day of December 1908.

IRVIN C. SMITH.
